UNITED STATES PATENT OFFICE.

PETER L. LARSON, OF CHICAGO, ILLINOIS.

COUNTERBALANCED STAIR.

No. 908,782.

Specification of Letters Patent.

Patented Jan. 5, 1909.

Application filed May 25, 1908. Serial No. 434,964

To all whom it may concern:

Be it known that I, PETER L. LARSON, a citizen of the United States, and resident of Chicago, county of Cook, and State of Illinois, have invented a certain new and useful Improvement in Counterbalanced Stairs, of which the following is a specification, and which is illustrated in the accompanying drawings, forming a part hereof.

The invention relates to stairs adapted to turn about a horizontal pivot and, more particularly, to those which are pivotally secured at their upper end to the edge of a platform such as that of the balcony of a fire escape. In practice these stairs are employed for connecting the balcony of a fire escape with the ground and in order that when not in use they may not provide a means of access to the building to which the fire escape is applied and may not obstruct the passageway below, they are so counterweighted that they normally rest in a substantially horizontal position, but are easily depressed to connect with the ground by pressure applied to the treads of the stairs.

As usually constructed the counterweights of these stairs take the form of an extension of the stair projecting beyond its pivot at the higher end. In order that this counterweight may clear the platform to the edge of which the stair is connected it is necessarily applied to one side only of the stair frame. In this construction there is a tendency of that part of the uncounterweighted side of the stairs remote from the pivot to sag, and the object of this invention is to correct the distortion which this sagging would otherwise produce.

The invention is exemplified in the structure to be hereinafter described and shown in the accompanying drawings, wherein—

Figure 1 is a perspective view of a counterweighted stair embodying the features of the invention; Fig. 2 shows in side elevation a detail of the construction separated from other parts; Fig. 3 is a detail transverse sectional view of the stair illustrated in Fig. 1; Fig. 4 is a side elevation of the stair illustrating the relative disposition of its parts before being hung upon its pivotal support. Figs. 5 and 6 are detail sectional views, and taken on the lines 5—5 and 6—6 of Figs. 1 and 3 respectively.

As shown, the stair comprises side members which are generally designated by the numerals 10 and 11 in the drawings. These

side members are connected by the treads generally designated 12. Preferably each of the side members comprises a pair of parallel bars 15, 16—one of which is shown in detail in Fig. 2 of the drawings. The bars of each pair are connected adjacent the higher end of the stair by plates 17, which are apertured to receive the pivotal support 18. The pivotal support which is shown takes the form of a rod 18 projecting horizontally from the wall 19 of the building to which the stair is applied. At the lower end of the stair the bars 15, 16 of each pair are connected by foot pieces 20. The treads 12 may be of any convenient form of construction and as shown, each comprises a plurality of parallel rods 21, each having its ends fitted into cross pieces 22, 23 and the treads are secured to the side members 10, 11 of the stair by securing the cross pieces 22, 23 to the bars 15, 16, of which the side members are composed, by bolts 24, as most clearly shown in Figs. 3 and 6 of the drawings.

Preferably the counter weight provided for normally supporting the stair in a substantially horizontal position, takes the form of a plurality of weights 25. As shown, these weights are fitted into a channel member 26 to which they are detachably secured by bolts 30. The channel member may be applied to one of the side members, as 10, of the stair adjacent its higher end and extends beyond the pivot 18, as shown at 27. A second channel member 28 is secured to the channel member 26 adjacent its outer end for supporting additional counter weights 29. As this counter weight is applied to but one of the side members, as 10, of the stair, there is a tendency for the free end of the uncounterweighted side member 11 to sag. Such a sagging would give the stair a distorted and unsightly appearance. In carrying out the invention, this distortion is prevented by so applying the treads 12 to the side member 10 that before the stair is hung upon the pivotal support 18 and before the application of the counter weights 25, 29 to the channel members 26, 28, the treads occupy a spiral relation, as shown in Fig. 4 of the drawings.

Most conveniently this spiral relation of the treads is effected by twisting each of the side members 10 and 11 about its longitudinal axis before the connection of the treads thereto. When each of the side members 10 and 11 is formed from a pair of bars 15, 16,

as shown, this twisting of the side members is effected by a twisting of the bars 15, 16 before their connection by the pivot plates 17 and foot pieces 20 to the form illustrated 5 in Fig. 2. In then connecting the treads 12 to the side members 10 and 11, the bars 15, 16 are strained by a drawing up of the bolts 24 to fit snugly against the end pieces 22, 23 of the treads and this straining of the bars 15, 10 16 causes the end of the side member 11 to incline upwardly towards its outer free end, as shown in Fig. 4. When constructed in 15 this way and hung upon a horizontal pivot 18, the greater sagging of the outer free end of the side member 11 of the stair than of the outer free end of the member 10, because of the application of the counter weights, 25, 29 to the channel bars 26, 28 secured to the member 10, produces a sufficient torsional 20 strain in the bars 15, 16 of each of the side members 10 and 11 to arrest the sagging when the parts have been brought to the undistorted position illustrated in Figs. 1 and 25 3 of the drawings. If, however, from any chance, as by too great a twisting of the bars 15, 16 of the side members 10 and 11, the

stair presents a distorted appearance when the parts have been assembled and mounted in the position of service, this distortion may be corrected by a twisting of the stair as a 30 whole by grasping the outer free ends of the side members 10 and 11 and by then hammering upon the twisted parts of the bars 15, 16.

I claim as my invention:—

In combination, a stair adapted to turn about a horizontal pivot comprising side members and treads connecting the side members, and a counterweight applied to one side only of the stair, the treads of the 40 stair being secured to the side member at the counterweighted side of the stair in spiral relation, whereby they are brought into parallel relation by the torsional strain produced in that side member by the tendency 45 of that part of the uncounterweighted side of the stair remote from the pivot to sag.

PETER L. LARSON.
